DESIGN FOR A ROTARY TOOTHBRUSH

Charles L. Rosengard, Hartford, Conn.

Application January 5, 1944, Serial No. 112,174

Term of patent 7 years

(Cl. D9—2)

To all whom it may concern:

Be it known that I, Charles L. Rosengard, a citizen of the United States, residing at Hartford, in the county of Hartford and State of Connecticut, have invented a new, original, and ornamental Design for a Rotary Toothbrush, of which the following is a specification, reference being had to the accompanying drawing, forming part thereof.

Figure 1 is a top plan view of a rotary toothbrush embodying my new design;
Figure 2 is a front elevational view thereof; and
Figure 3 is a side elevational view thereof.

I claim:

The ornamental design for a rotary toothbrush, substantially as shown.

CHARLES L. ROSENGARD.
